Primary Examiner — Darlington Ly*(74) Attorney, Agent, or Firm* — Faegre Drinker Biddle & Reath LLP(57) **CLAIM**

The ornamental design for a saddlebag for a two-wheeled vehicle, as shown and described.

DESCRIPTION

FIG. 1 is a front and right side perspective view of a right side mounted saddlebag for a two-wheeled vehicle embodying our new design;

FIG. 2 is a front elevation view thereof;

FIG. 3 is a rear elevation view thereof;

FIG. 4 is a right side elevation view thereof;

FIG. 5 is a left side elevation view thereof; and,

FIG. 6 is a top plan view thereof.

The portions of the saddlebag shown in broken lines form no part of the claimed design.
